UNITED STATES PATENT OFFICE.

HARRY R. PATTERSON, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO.

ENGINE-PRIMING DEVICE.

Application filed November 28, 1919. Serial No. 341,195.

To all whom it may concern:

Be it known that I, HARRY R. PATTERSON, a citizen of the United States, residing at Toledo, in the county of Lucas and State of Ohio, have invented certain new and useful Improvements in Engine-Priming Devices, of which I declare the following to be a full, clear, and exact description.

This invention relates to internal combustion engines and particularly to engines of that type which are intended to operate on a fuel which is not readily vaporized when the engine is cold.

It is an object of my invention to provide means for supplying to the engine for starting when cold a more volatile fuel upon which the engine may be operated until it has developed sufficient heat to permit its operation upon the less volatile fuel employed for normal running.

Another object of my invention is the provision in such an arrangement of means whereby a more volatile fuel may flow to the engine only during starting of the same when the air supply is restricted.

A further object of my invention is the provision of means for restricting the flow of the less volatile fuel to the engine when the connection to the more volatile fuel is open and the air supply is restricted the arrangement being such that by means of a single actuated member the more volatile fuel only may first be admitted to the engine and subsequently as this supply is diminished, the less volatile fuel be admitted in increasing quantities.

Further objects of this invention relate to economies of manufacture and details of construction as will hereinafter appear from the detailed description to follow. I accomplish the objects of my invention in one instance by the devices and means described in the following specifications, but it is evident that the same may be varied widely without departing from the scope of the invention as pointed out in the appended claims. A structure constituting one embodiment of my invention, which may be the preferred, is illustrated in the accompanying drawings forming a part thereof, in which:

Figure I shows in vertical cross section a portion of the cylinder of an internal combustion engine together with fuel supplying and vaporizing means therefor comprising

my invention. Fig. II is a horizontal cross section on the line II-II of Fig. I and Fig. III is a cross sectional view taken on the line III-III of Fig. II.

In the drawings, the same reference numerals refer to similar parts throughout the several views, and the sectional views are taken looking in the direction of the arrows at the ends of the section lines.

On the drawing there is represented at 5 the upper portion of the cylinder of an engine of the "Knight" sleeve valve type having a piston 6 and sleeve 7 to control the inward flow of fuel from the inlet chamber 8 and the exit of the burned gases into 70 the exhaust chamber 9. Connecting with the inlet chamber 8 is a tubular member 10 which comprises a horizontal portion 11 and a vertical portion 12. The horizontal portion 11 has a passage therethrough in the 75 form of two connecting truncated cones 14 and 15 forming what is commonly known as a Venturi tube. Within the conical portion 15 there is mounted a nozzle and valve member 16. This member has an opening there- 80 through in alignment with the axis of the cones 14 and 15 and has a reduced portion 17 which constitutes a valve seat. The forward end of this member, that is, the end toward the engine, lies substantially at the 85 narrowest portion of the Venturi tube where the suction due to the passage of air therethrough is the greatest. A pipe 20 extending up from a fuel tank 21 adapted to contain a fuel for normal operation of the engine such for example as kerosene, connects with the nozzle member 16 by means of a needle valve 22 having an operating handle 23. The tank 21 may be located in any convenient position such as in the base of the 95 engine and, if desired, a ball valve 24 may be employed at the lower end of the pipe 20 to maintain the fuel level in the supply pipe.

Beyond the Venturi tube the member 10 100 is formed with a circular bore 30 in which slides a hollow plug 31. An end plate 32 screwed into the end of the member 10 has an annular portion 33 which extends within the plug 31 and serves to carry one end of a 105 coil spring 34 whose opposite end engages under the head of a push plate 35 secured to an operating rod 36. To prevent the plug 31 from turning it is provided with a spline 37 in which slides the end of a screw 38. 110

Inward movement of the plug 31 is limited by a shoulder 39 and when the plug is in contact with this shoulder, the main air supply to the engine is cut off. The outer portion of the circular bore 30 is provided with an annular chamfer 40 which connects with a small hole 41 in the plug by means of an elongated opening 42 in the side of the plug. The length of this elongated opening 42 is so proportioned relative to the chamfer 40 that when the plug is moved to its extreme forward or inward position, communication between those parts is almost entirely cut off, a passage being left only sufficient to allow a small quantity of air to pass to provide for vaporizing the auxiliary fuel and for the proper combustion thereof in starting the engine. Extending upward from a small auxiliary fuel tank 44, which is adapted to contain some lighter or more volatile fuel, as for example, gasoline, benzine or alcohol, is a pipe 45 which enters the member 10 at the side and is adapted to register with the elongated opening 42 when the plug is moved inward but is cut off when the plug is in its normal retracted position, illustrated by Fig. II.

The rod 36 is provided with a forwardly extending, axially located valve rod 47 having a tapered end 48 forming a valve which when the plug is moved to its extreme inward position passes through the member 16 and engages the reduced portion or valve seat 17 upon which it seats to close off the flow of fuel from the tank 21. The member 16 is constructed to engage the valve rod 47 with a snug fit at the end opposite the valve seat but the intermediate portion is constructed with sufficient clearance to permit the free flow of fuel past the rod when the valve is open.

The operation of the device is as follows.

Suppose that the engine is cold and it is desired to start the same. The throttle valve 22 controlling the flow of fuel from the main supply tank 21 will first be opened the desired amount to operate the engine. The crank shaft of the engine will then be given one or more revolutions by hand or other means at the same time pressing upon the push plate 35 to hold the plug 31 against its seat 39. In this position, the flow of fuel from the main supply tank will be shut off by the valve 48, the main air supply will also be closed but the connection to the auxiliary fuel tank 44 will be open. The lighter or more volatile fuel contained in the auxiliary tank will thereupon be vaporized and drawn into the engine. After the engine has made a few revolutions, using this auxiliary fuel, it will have developed sufficient heat to readily vaporize and run on the heavier or less volatile fuel contained in tank 21. Pres-
sure upon the push plate 35 may then be

gradually withdrawn permitting the plug 31 and valve 48 to be withdrawn whereby the regular operating fuel may flow to the engine, the air supply opened and the valve controlling the auxiliary fuel supply closed. The change from operation upon the starting fuel to operation upon the regular operating fuel may, by this apparatus, be made gradual, the two fuels blending one with another during the starting operation. After the engine is under way and operating on the heavier fuel, pressure upon the push plate is entirely released, whereby the engine is given an unrestricted supply of air and the connection to the supply of starting fuel is completely cut off.

While I have described my invention in more or less detail, and as being embodied in certain precise forms, I do not desire or intend to be limited thereto, as on the contrary my invention contemplates broadly all proper changes, as well as the omission of immaterial elements and the substitution of equivalents therefor, as circumstances may suggest or necessity render expedient.

Having thus described my invention, what I claim as new and desire to secure by Letters Patent, is:

1. In a device of the class described, the combination of an internal combustion engine having a fuel inlet, a tubular element connected to the fuel inlet, said tubular element having two fuel openings and one air opening; a plurality of valvular members fixedly interconnected, adapted to open and close said openings; and means for operating said valvular members.

2. In a device of the class described, the combination of an internal combustion engine having means for supplying fuel thereto, a valve for controlling the supply of said fuel, a valve for controlling the amount of air supplied to said engine, means for supplying a more volatile fuel to said engine for starting, and a member adapted to be actuated in starting said engine to close said fuel supply valve and said air supply valve whereby said more volatile fuel is drawn into the engine, said fuel supplying and controlling means being directly interconnected.

3. In a device of the class described, the combination of an internal combustion engine, means for supplying and vaporizing liquid fuel therefor including a Venturi tube, a valve for controlling said supply, positioned at the constricted point of said Venturi tube a valve for controlling the air supply to said engine, means including a valve for supplying a more volatile fuel to said engine for starting and a single manually operable means for operating all said valves.

4. In a device of the class described, the combination of an internal combustion engine, having a fuel inlet, a mixing chamber

connected to said inlet, said chamber having two fuel openings and an air opening, valves for closing said fuel and air openings, and single means for simultaneously closing one 5 of said fuel valves and said air valve and opening the other of said fuel valves.

5. In a device of the class described, the combination of an internal combustion engine, having a fuel inlet, a mixing chamber 10 connected to said inlet, said chamber having

two fuel openings and an air opening, valves for closing said fuel and air openings, single means for simultaneously closing one of said fuel valves and said air valve and opening the other of said fuel valves, and an air leak- 15 age conduit opening into said mixing chamber.

In testimony whereof, I affix my signature.

HARRY R. PATTERSON.
